UNITED STATES PATENT OFFICE.

PALEMON H. GASKINS, OF JACKSONVILLE, FLORIDA.

MUFFLER.

Application filed November 10, 1921. Serial No. 514,243.

To all whom it may concern:

Be it known that I, PALEMON H. GASKINS, a citizen of the United States, and a resident of Jacksonville, in the county of Duval and State of Florida, have made certain new and useful Improvements in Mufflers, of which the following is a specification.

The present invention relates to an improvement in mufflers or silencers for use in internal combustion engines.

The object of the invention is to provide a muffler of this character which is of simple and durable construction, reliable and efficient in operation and easy and comparatively inexpensive to manufacture, and wherein there is provided a cut-out for automatically relieving the muffler of excessive pressure and the engine of excessive back pressure, the cut-out being of such nature and so organized that the muffler has to provide a direct and unobstructed passage for the gases from the engine to the atmosphere when it is open and yet at the same time to discharge these gases clear of the body of the vehicle, and not under the same and in such manner as not to cause disagreeable and undesirable noise, whereby the liability of these gases discoloring and injuring the vehicle and of detracting from the comfortable and agreeable qualities thereof, if it be a pleasure vehicle, is precluded.

Other objects and advantages of the invention reside in certain novel features of construction, combination and arrangement of parts, which will be hereinafter more fully described, and particularly pointed out in the appended claim, reference being had to the accompanying drawings forming part of this specification, and in which:

Figure 1 is a perspective view of the muffler embodying the invention;

Figure 2 is a view thereof in longitudinal vertical section, and,

Figure 3 is a view in transverse section on line 3—3 of Figure 2.

Referring to the drawings, wherein for the sake of illustration is shown the preferred embodiment of the invention, the numeral 10 designates an exhaust pipe, which

leads from the internal combustion engine. A muffler designated generally at 11 is carried by brackets 12, which depend from the body 13 of the vehicle and is connected with the exhaust pipe in a manner which will presently appear.

The muffler comprises a pair of heads 15 between which a cylindrical casing 16 extends. The casing 16 is preferably constructed of metal and is imperforate and its ends are connected with the heads 15 in such manner as to provide a gastight joint between the heads and the casing. Within the casing 16 a plurality of perforated drums indicated at 17 and 18 are arranged in spaced concentric relation with relation to the casing. These drums define annular expansion chambers 19 and 20 and the inner drum 18 communicates at one end with the exhaust pipe 10, which leads into an opening provided therefor in one of the heads 15, and which is co-axial with the inner drum 18.

An annular flange 21 is integrally formed with the head 15 and receives the end of the exhaust pipe 10, a set screw 22 being carried by the flange and engaging the exhaust pipe to secure it in position.

Tie rods 23 having nuts 24 threaded thereon coact with the arms 12^a of the brackets 12, and with the heads 15 of the muffler to secure the muffler in position, and also to secure the heads to the casing and to the drums, if this latter be desired.

A tail pipe designated at 25 is provided, and is associated with the muffler by means of a connection designated generally at 26. The connection 26 is formed with a passage 27 leading from the tail pipe 25 to the inner drum 18 of the muffler, and it is also formed with a second passage 28 which leads from the tail pipe 25 to the outer expansion chamber 20, that is, to the space between the outermost drum 17 and the casing 16. The passage 27 is provided with a valve seat 27^a which may be constituted by the end of the inner drum 18 of the muffler by projecting this end of the muffler into the passage 27. A valve 30 is arranged to coact with this valve seat, and for this purpose it is fixed on a pivot pin 31 rotatably mounted

in suitable bearings provided therefor in the connection, whereby the valve 30 is mounted for swinging movement and is adapted to coact with the valve seat 27^a or to be swung 5 away from the same.

Means is provided for normally maintaining the valve 30 in engagement with the valve seat 27^a to constrain the gases to pass to the expansion chambers in the mufflers 10 and flow out of the muffler through the passage 28 into the tail pipe. This means preferably comprises an operating arm 32 fixed to the pivot pin 31 exteriorly of the connection 26 and secured to one end of a 15 retractile coil spring 33, the other end of which is secured to the tail pipe or to other stationary structure.

The retractile coil spring 33 is tensioned to exert a pull upon the operating arm so 20 as to urge the valve 30 up against the seat 27^a and shut off communication between the inner drum 18 and the passage 27.

The tension of the spring 33 is sufficient to maintain the valve 30 closed until the 25 pressure in the muffler reaches a predetermined point. At this time the spring is extended to permit the valve 30 to swing down away from the valve seat 27^a thus opening the passage 27 to permit the gases to flow directly and unobstructedly through the muffler to the tail pipe, and thence to the atmosphere. This tension is such as to relieve the muffler of excessive pressures and also to relieve the engine of excessive back 30 pressure.

Operating means is provided for swinging the valve 30 away from the seat 27^a against the tension of the spring 33, at any time, and may comprise an operating cord 40 36 connected with the arm 32 and extending to the dash of the vehicle or to other point of convenient control.

The valve 30 may be readily assembled with the connection by inserting it up 45 through the passage 28, which has a sufficient lateral extent to permit of this operation. The valve is then held in position on its valve seat 27^a, and the pivot pin 31 is inserted through its bearings or journals in 50 the connection and through the opening provided therefor in the valve 30.

It is to be noted that the drum 18 affords a direct passage through the muffler when the valve 30 is swung away from the seat 55 27^a and also that the expansion chambers 19 and 20 are in series with each other and in series with the passage 28 of the connection 26.

In operation, when the engine is running 60 under normal conditions and at ordinary speeds the exhaust gases flow through the exhaust pipe 10 and into the inner drum 18 of the muffler. From this inner drum they are expanded radially through the various 65 expansion chambers 19 and 20 and from the

expansion chamber 20 and flow through the passage 28 which is enlarged to form another expansion chamber and finally they travel through the tail pipe 25 to the atmosphere. At high speeds and at such times as a high 70 degree of power is required of the engine, the exhaust gases are delivered to the muffler in such quantity and in such manner that the pressure in the muffler becomes excessive. This tends to create an excessive back pressure 75 to the engine and at the very time it is desirable to have as little back pressure as possible. With the present invention when this condition obtains, the valve 30 is swung from its seat 27^a, thus affording direct, free 80 and unobstructed communication between the inner drum 18 and the tail pipe 25, and allowing the exhaust gases to pass directly from the engine to the atmosphere without constraining these gases to travel through 85 the various expansion chambers of the muffler. At the same time, however, these gases travel through tail pipe to the atmosphere so as to be discharged clear of the body 90 of the vehicle, and not to be discharged beneath the same so as to be liable to inflict injury thereto and to produce disagreeable and undesirable noise. In this connection it is to be noted that even when the valve 30 is opened or away from its seat 27^a the exhaust 95 gases while having a direct and unobstructed passage to the atmosphere are not discharged beneath the car but are delivered to the tail pipe and discharged clear of the car. This prevents noise directly beneath the floor 100 boards of the car which is one of the most serious objections to the mufflers now employed. If at any time it is desirable to manually open the cut-out 30, the operating cord 36 is pulled, to swing the valve 30, so 105 as to permit the drum 18 to discharge directly into the passage 27 and consequently directly into the tail pipe 25.

I claim:

In a device of the character described, an 110 exhaust pipe, a muffler comprising an imperforate cylindrical casing and a plurality of perforated drums arranged in spaced concentric relation with said casing and defining a series of expansion chambers, the inner 115 of said drums being connected with the exhaust pipe, a tail pipe, a connection between said tail pipe and said muffler having a passage leading to the expansion chamber defined by the outermost of said perforated 120 drums, and said casing, and a passage leading to the innermost of said drums, said last mentioned passage having a cross sectional area substantially coextensive with the cross 125 sectional area of said innermost drum, a valve seat around one end of the innermost drum and in said passage leading to the innermost of said drums, an imperforate pivoted plate valve arranged in said connection and adapted to cooperate with said valve seat, 130

said valve having an area exposed within the innermost drum equal to the cross sectional area of said innermost drum, spring means for normally maintaining said valve against said valve seat to shut off communication between the innermost drum of the muffler and the tail pipe, and adapted to permit said valve to move so as to afford communication between said innermost drum and said tail pipe when the pressure in said muffler exceeds a predetermined point, and manually operated means for moving said valve against the action of said spring.

PALEMON H. GASKINS.
